FLOOR MACHINE HOUSING UNIT

William E. Holt, Oakland, Calif.

Application April 11, 1957, Serial No. 45,686

Term of patent 14 years

(Cl. D9—2)

FIG. 1

FIG. 2

FIG. 3

Fig. 1 is a side elevational view of a floor machine housing unit showing my new design;

Fig. 2 is a rear elevational view of the housing unit; and

Fig. 3 is a top plan view thereof as shown in Fig. 1 with a portion of the handle assembly omitted for illustrative purposes only.

I claim:

The ornamental design for a floor machine housing unit, as shown and described.
